UNITED STATES PATENT OFFICE.

WALTER C. CARTER, OF PITTSBURGH, PENNSYLVANIA.

GAME-BOARD.

1,204,246.

Specification of Letters Patent.

Patented Nov. 7, 1916.

Application filed April 15, 1916. Serial No. 91,400.

To all whom it may concern:

Be it known that I, WALTER C. CARTER, a citizen of the United States, residing at Pittsburgh, in the county of Allegheny and State of Pennsylvania, have invented certain new and useful Improvements in Game-Boards, of which the following is a specification, reference being had to the accompanying drawings.

10 This invention relates to game boards, and particularly to games on the order of checkers or chess, and the object of the invention is the provision of a game board so formed that a modification of the game of checkers may be played thereon, the board being so constructed that two, three or four 15 players may play at one time, the design of the board being such that the moves are rendered more complicated than in an ordinary game of checkers and the game made much more interesting.

15 The invention is illustrated in the accompanying drawing, wherein:

Figure 1 is a plan view of a board constructed in accordance with my invention; 20 and Fig. 2 is a fragmentary plan view showing the use of circular checks in place of square.

25 Referring to Fig. 1, 2 designates a board of any suitable material, the field of this board being square and being divided into 169 squares or checks, 84 of which are white squares and 85 of which are squares having a different color, as for instance, black or 30 red. The white squares are arranged alternately to the colored squares, as clearly seen from the drawing. The central square or space, which is designated 3, is preferably of a different color from the squares immediately surrounding it, as for instance, red, 35 if the squares immediately surrounding it are black, and preferably is circular in form. Surrounding the central check or circle 3 are 25 black squares, or squares of a contrasting color to the central check, these 40 squares being arranged in a square, designated 4, the sides of which extend diagonally to the sides of the board or field. The space inclosing these 25 squares is preferably outlined by a line 5 touching the corners of the black squares inclosed within the space 4. Exteriorly to the line 5, and extending parallel to this line, there are 24 45 squares designated 6, which are preferably red or the same color as the central check 3.

This leaves 9 squares at each corner of the board which are black. The space inclosed within the line 5 is called the "king's square," and the central check 3 is called the "king's circle."

60 The game is played with ordinary checkers, or like pieces, and is played similarly to checkers, only the players start from the corners of the board and play toward the center. In playing, the object of any one 65 player is of course to jump the men of any other player and remove them from the board and also get the pieces one by one into the king's square, that is, the space inclosed within the line 4 and to get the pieces one 70 by one onto the king's circle 3. As soon as a piece moves into the king's square it has all the attributes of a king, that is, it can jump in all directions, but it is not crowned, and the piece can only be crowned after it is 75 moved onto the king's circle 3. After a piece has been moved into the king's square, as before remarked, it has all the attributes of a king except that it cannot be played outside of the king's square. After a piece 80 has been crowned, however, it then has free movement over the entire board in any direction.

85 While I have illustrated in Fig. 1 a board laid off into squares, this is not necessary as it may be laid off in circles as illustrated in Fig. 2, in which case, however, preferably the central square 3 has the form of a square to distinguish it from the circles.

90 It will be seen that the game lends itself to any number of players from two to four because it is played toward the center of the board, and furthermore, that because of the subdivision of the board into the king's square and the king's circle the playing of 95 the game is rendered much more complicated and interesting. It is particularly essential in this game that the king's square 4 should have a sufficient number of checks in it to permit uncrowned kings within this 100 square to have free movement over a relatively large extent of board, as otherwise the defense of the king's square against an adversary would be too easy, and one or two kings within the king's square, even 105 though they had not been crowned, would render it extremely difficult for an adversary to move his pieces into the king's square. Furthermore, by providing the red checks 6 which bound the red line 5, this red line is 110

emphasized, and again special rules may be made for playing upon this line of red checks.

It will be noted that the checks 6 which bound the king's square or space extend diagonally across the field so as to leave at the corners of the field a certain number of checks, illustrated as 9 in number, which define the space within which the players dispose their men at the beginning of the game. In view of the fact that the checks upon which the pieces move may be either round or square or have any other desired form, I will hereafter in the claims define these spaces as checks instead of squares.

Having described the invention, what I claim is:

1. A game board having a square field laid off in alternate different colored checks and having a centrally disposed king's check of one color surrounded by a king's space having checks of a different color from the central check, said king's space being square and defined by a line of con-

trasting color to the checks, the sides of the 25 king's space extending diagonally with relation to the sides of the field.

2. A game board having a square field laid off in alternate different colored checks and having a centrally disposed king's 30 check of one color surrounded by a king's space having checks of a different color from the central check, said king's space being square and defined by a line of contrasting color to the checks inclosed therein, 35 the sides of the king's space extending diagonally to the sides of the field, the alternate sections exterior to the line and touching the line at the corners being of the same color as the line and as the king's check 40 but differing in color from the other checks.

In testimony whereof I hereunto affix my signature in the presence of two witnesses.

WALTER C. CARTER.
